CLAIM

The ornamental design for a compact pedal board for electronically-operated musical instruments, as shown and described.

DESCRIPTION

FIG. 1 is a front, top and left side perspective view of a compact pedal board for electronically operated musical instruments showing our new design;

FIG. 2 is a top plan view;

FIG. 3 is a front elevational view;

FIG. 4 is a rear elevational view; and

FIG. 5 is a left side elevational view, the opposite side being a mirror image thereof.

The bottom of the pedal board is flat and unadorned.

FIG. 1.

FIG. 2.

FIG. 3.

FIG. 4.

FIG. 5.
